UNITED STATES PATENT OFFICE

GUSTAVE O. DEGENER, OF NEW YORK, N. Y., ASSIGNOR TO ROYAL TYPEWRITER COMPANY, INC., OF NEW YORK, N. Y., A CORPORATION OF NEW YORK

TYPEWRITING MACHINE

Application filed December 12, 1927. Serial No. 239,490.

This invention relates to platen shift mechanism particularly adapted to be used in connection with a power actuated machine such as shown in my prior application Ser. 5 No. 243,067, filed Dec. 28, 1927, although capable of use in other types of power driven machines. The platen is normally held in its lower position and is moved to the upper case position by means of a spring. The power 10 means is employed to return the platen to the lower position in opposition to the spring. Upon a depression of the platen shift key, the latch which normally holds the platen in the lower position is released and the 15 spring immediately moves the platen upward to upper case position. At the same time this movement of the platen starts the motor if the latter is not already running. A second latch is moved by the key into 20 position to hold the platen against accidental displacement from its upper case position.

As soon as the key is released the power operated mechanism is permitted to come into action and the platen will be returned 25 to its lower case position against the action of said spring while the operation of the latches will be exactly the reverse of that which takes place upon the depression of a key.

30 Further features of the invention will be apparent from the following detailed description and set forth in the appended claims.

In the drawings:

35 Figure 1 is a fore and aft section through the machine with parts in side elevation showing the invention and mechanism in its normal position.

40 Figure 2 is a similar view showing the parts in position which they occupy when the key is depressed.

45 Figure 3 is a fragmentary view showing the key returned to normal position and the power operated mechanism in action.

Figure 4 is a side elevation disclosing the manner in which the power mechanism is connected to the shift frame.

50 Figure 5 is a side elevation illustrating the latch mechanism with parts in slightly different position.

A shift key lever 1 is pivoted to turn about an axis 2 and is held in normal position by means of a spring 3 one end of which is attached to the key lever and the other end to a plate 4 carried by a transverse bar 5. A 55 stop 6 engages the key lever and limits its movement under the influence of the spring 3. An upward extension 7 of the key lever is connected by link 8 to a latch member 9 pivoted on an axis 23. This latch member 9 60 has a hook 10 which when the platen is in lower case position engages over a projection or stop 11 on the shift frame and holds it in lower case position.

Although the invention is applicable to 65 different types of machines it is herein illustrated as being applied to the standard Royal machine. This construction comprises a shift frame A having a connecting link a and a track rail B upon which is guided a 70 track rail C of the carriage D which latter supports the usual platen E. The two case shift positions of the platen are determined by the usual adjustable stops F and G.

The whole shift frame is normally urged 75 towards its upper case shift position by means of a spring 12 which is attached at one end of a portion 13 of the shift frame and at its other end to a member 14, the position of which can be adjusted by the usual mechanism 15 for the purpose of varying the tension of the platen shifting spring.

Whenever the shift key 1 is depressed the hook 10 is moved out of engagement with the projection or stop 11 and the spring 12 85 thereupon moves the platen to its upper case position in which a projection 16 on the shift frame contacts with a stop F on the main frame as shown in Figure 2.

A lever 18 is pivoted at 19 to the upward- 90 ly extending arms 7 of the shift key lever and has connected to its upper end a spring 20, the other end of which is attached to an ear on the arm 7. This causes the arm 7 and the lever 18 to move together normally 95 but permits independent movement thereof. The lever 18 is connected by a link 21 to a latch member 22 which is also pivoted on the axis 23. The upper end of this latch has a cut out 24 forming a shoulder which is 100

adapted to engage beneath the shift frame stop 11 and to lock the platen in upper case position, as shown in Figure 2. The link 8 is connected to the latch 9 above its pivot 23 and the link 21 is connected to the latch 22 below said pivot. The extension 25 on the shift key lever limits the downward movement thereof by coming into contact with the underside of a plate 26 carried by a transverse frame bar 27.

When the parts are in the normal position shown in Figure 1, the hook 10 overlies the shift frame stop 11 while the latch member 22 lies somewhat in front of said stop. During the first part of the depression of the key lever the parts first move to the Figure 5 position in which the hook 10 is nearly disengaged from the stop 11 and the latch 22 has been moved into contact with the said stop. A slight further depression of the shift key lever causes the hook 10 to release the stop 11 and also tensions the spring 20 so that when the platen moves to its upper case position under the influence of the spring 12, the latch member 22 will immediately snap under the stop 11 to the holding position shown in Figure 2. On the return movement of the shift key lever the latch members will be operated in the reverse order, the latch 22 being first moved out of engagement with the stop 11 in order to permit a power mechanism to return the platen to lower position and thereafter the latch member 9 is moved so that the hook 10 engages over the stop and the parts are again held in the Figure 1 position.

Whenever the platen moves to the upper case position under the influence of the spring 12, an arm 28 on the shift frame A engages the upper end of a lever 29 pivoted to the frame at 30 and this lever is connected by a link 31 to a means for starting an electric motor, which is clearly set forth in my above mentioned application. So far as the invention herein claimed is concerned, it is immaterial what means is employed for starting the motor so long as it is actuated by the movement of the shift frame. Of course in many cases a motor will be already running and this movement will be merely an idle movement. However, if the motor is not running, it is evident that a depression of the shift key lever will release the platen when in its lower case position from its latch mechanism, that the platen will be then moved to the upper case position, and that this upward movement of the platen will immediately start the motor.

It now remains to consider the mechanism by which the power is employed to return the carriage and platen to their lower case position upon the release of the shift key lever. An intermediate portion of the shift key lever 1 has a cut out 32 and a plate 33 carried by the key lever extends

downwardly and terminates in a generally horizontal portion 34 at its lower end, the spring and horizontal portion being so positioned that it closes both of the open sides of the cut out 32.

A power or actuating lever 35 is pivoted on an axis 36 carried by the transverse frame bar 27 and is held in normal position by a spring 37 attached at one end to the power lever and at its other end to the plate 26 while a projection 38 on the power lever is adapted to engage with the transverse bar 27 to limit the movement of the lever under influence of the spring 37. An upwardly extending arm 39 on the power lever is connected by a link 40, one end of which engages in a slot in said arm and the other end of the link is connected to the upper arm 41 of a bell crank lever pivoted at 42 on the frame of the machine. The other arm 41' of this bell crank lever is guided between a flat depending portion of the connecting link α and an offset lug 43 which is bent out of said link. This arm 41' terminates in an ear 44 which is connected by a spring 45 to an ear 46 on the connecting link α . It is therefore apparent that if the power lever is moved to exert a pull on the link 40 this will actuate the bell crank lever 41 and the spring 45 being stronger than the spring 12 will return the platen to its lower case position. The use of the spring 45 however, avoids any sudden jerks and cushions the whole returning movement.

A shaft 51 which is provided with a plurality of projections 52 is driven from a suitable source of power, such as an electric motor, as set forth in my above mentioned application. The ends of the fingers or projections 52 form arcs of a circle concentric with the axis of said shaft. A star wheel 47 is pivoted at 48 on the power lever and a spring plate 49 causes the star wheel and lever normally to move together but permits independent movement of the star wheel. This wheel has a plurality of arms or fingers 50 in the ends of which are depressions 53 which correspond in curvature with the ends of the projections or fingers 52 on the power shaft 51.

The front end of the lever 35 is provided with an offset extension 54 which extends above the upper edge of the lever and as shown in Figure 1, normally rests against the portion 34 of the spring 33. Whenever the key lever 1 is depressed this extension 54 will be moved off the spring 34 and rest in engagement with a portion 55 on the under edge of the key lever 1, as shown in Figure 2. It is to be noted that the horizontal portion 34 of the spring is at a slightly lower level than the portion 55 so that on a return movement of the key lever the offset 54 will contact with the end of the horizontal portion 34, thus flexing the spring which will permit the

extension 54 to pass up into the cut out 32. This movement permits the rear end of the lever 35 which carries the star wheel to drop until one of the arms 50 of the star wheel will be engaged and operated by a finger 52 on the 5 rotating shaft 51, in the same manner as set forth in my above mentioned application. It is obvious that such action will produce an upward movement of the portion of the power lever 35 in the rear of its pivot 36 and this movement will pull forward on the link 40 and thereby return the platen E to its lower case position, as previously set forth. During this movement of the power lever by the 10 power mechanism, the forward end of the lever will be moved out of the recess 32, as shown in Figure 3, and the spring will thereupon close the entrance to said recess. It is to be remembered that this action does not 15 take place until the shift key lever is released so that the shift key lever will be in normal position by the time the power mechanism has returned the platen to lower case position and the power lever is permitted to 20 return to its normal position. This will bring 25 all parts once more to the Figure 1 position.

It is obvious that the invention in its broader aspects may be applied to different types of machines and used in connection 30 with different forms of latch mechanism. It is therefore to be understood that the invention is intended to include all modifications of form, proportions or construction which, 35 are covered by the scope of the appended claims.

I claim as my invention:

1. In a typewriting machine, a platen shift frame, spring means tending to move said frame to one of two positions, a latch preventing 10 such movement, key operated means for releasing said latch, and power operated means for returning the platen to normal position against the spring means.

2. In a typewriting machine, a platen shift frame, spring means tending to move said frame to one of two positions, a latch preventing such movement, key operated means for releasing said latch, and power operated means for returning the platen to normal position 50 against the spring means, said power operated means being brought into operation upon the release of the key operated means.

3. In a typewriting machine, a platen shift frame, a key, spring means which move the frame into upper case position upon a depression of the key, and power operated means for returning the frame to lower case position upon the release of the key.

4. In a typewriting machine, a platen shift frame, a key, spring means which move the frame into upper case position upon a depression of the key, power operated means for returning the frame to lower case position upon 15 the release of the key, and latches operated

by the key for holding the frame in either case position.

5. In a typewriting machine, a shift frame, means normally tending to move the frame to upper case position, a latch restraining 70 said means, key operated means for releasing the latch, power operated means including a normally inactive motor for returning the frame to lower case position upon release of said key operated means, and connections operated 75 by the frame in its movement to upper case position for starting the motor.

6. In a typewriting machine, a shift frame, means normally tending to move the frame to upper case position, a latch restraining said 80 means, key operated means for releasing the latch, a normally inactive motor, connections operated by the frame in its movement to upper case position for starting the motor, and power operated means operatively connected 85 with the motor for returning the frame to lower case position.

7. In a typewriting machine, a shift frame, means constantly tending to move the shift frame to upper case position, a latch for restraining 90 said movement, a key, connections from said key to the latch for moving the same to inoperative position, a second latch and yielding connections from the key to the second latch whereby case shift movement 95 is permitted and the second latch is permitted to function.

8. In a typewriting machine, a shift frame, means constantly tending to move the shift frame to upper case position, power operated 100 mechanism for returning the frame to lower case position, and yielding connections between the power operated mechanism and the shift frame.

9. In a typewriting machine, a shift 105 frame, means tending to move said frame to upper case position, a latch restraining said means, a key unconnected from the shift frame, a power driven shaft, a power lever normally out of operative relation with said 110 shaft, means for operating said latch upon the down stroke of the key to permit said means to move the shift frame, and means for permitting the power lever to move into operative relation with the shaft upon the 115 return movement of the key lever and thereby return the frame to lower case position.

10. In a typewriting machine, a shift frame, means normally tending to move the frame to one of two positions, a latch restraining 120 said means, key operated means for releasing the latch, power operated means including a normally inactive motor for returning the frame to normal position upon release of said key operated means, and connections operated by the frame in its movement to one of said positions for starting the motor.

11. In a typewriter machine, a shift frame, means normally tending to move the frame to 130

one position, a latch restraining said means, key operated means for releasing the latch, a normally inactive motor, connections operated by the frame in its movement to said 5 position for starting the motor, and power operated means operatively connected with the motor for returning the frame to the other position.

12. In a typewriter machine, a platen, shift 10 frame, a key, spring means for moving the frame into upper case position upon a depression of the key, and power operated means for returning the frame to lower case position.

13. In a typewriter machine, a shift frame movable from lower case position to upper case position, a spring for moving the shift frame from lower case position to upper case position, a latch for retaining the shift frame 20 in its lower case position against the tension of said spring, a power shaft, a power lever normally disengaged from said power shaft for moving the frame from upper case position to lower case position, and a key lever for 25 first disengaging the latch from the shift frame and for subsequently effecting engagement between the power lever and the shaft for actuating said lever to move the shift frame to lower case position against the tension of said spring before the completion of 30 the return movement of said key lever.

14. In a typewriter machine, a shift frame movable from one position to another, a power shaft having fingers formed with ends 35 located in arcs of a circle concentric with the axis of the shaft, a power lever normally disengaged from said power shaft for moving the frame to one of said positions, a star wheel pivoted to said power lever and 40 having extensions provided in their ends with depressions adapted to fit the ends of the fingers, and key controlled means normally holding said power lever so that the extensions on the star wheel are normally 45 out of the path of the fingers on said shaft, said key lever being adapted upon depression to effect engagement between the extensions and fingers to move the shift frame from one position to the other.

50 In testimony whereof, I have hereunto subscribed my name.

GUSTAVE O. DEGENER.
